The ornamental design for a moistened towelette dispenser, as shown and described.

DESCRIPTION

FIG. 1 is a bottom, front, and left side perspective view of a moistened towelette dispenser showing my new design;

FIG. 2 is a top plan view thereof;

FIG. 3 is a bottom plan view thereof;

FIG. 4 is a left side elevational view thereof, the right side being a mirror image of that shown;

FIG. 5 is a front elevational view thereof;

FIG. 6 is a rear elevational view thereof; and,

FIG. 7 is a top, front, and left side perspective view thereof, shown in an opened position.

The broken-line disclosure of a portion of the towelette roll in the views is for illustrative purposes only and forms no part of the claimed design.
